ELECTRIC DISCHARGE DEVICE

Willard H. Bennett, Newark, Ohio, assignor to
 Electronic Research Corporation, Newark,
 Ohio, a corporation of Ohio

Application June 28, 1941, Serial No. 400,276

14 Claims. (Cl. 250—27.5)

This invention relates to electric discharge devices and refers more particularly to improvements in electric discharge devices of the type wherein the electrodes are enclosed in a free electron gas or, in other words, in an atmosphere in which electron attachment to molecules does not readily occur.

When operating electric discharge devices in air, a sluggish pulsating form of discharge is obtained which may be attributed to the attachment of electrons to oxygen molecules to form molecular ions which have a much smaller mobility than electrons and appreciably suppress ionization in the sheath. As a result, electric discharge devices operating in an atmosphere containing oxygen supply relatively low currents for a given applied voltage and are inefficient.

Generally speaking it may be said that the operating efficiency of rectifiers depends on the rapidity of movement of electrons on the forward or useful half cycle and on the degree of obstruction offered to movement of ions on the inverse half cycle.

In order to arrive at the above condition, the electric discharge was effected in an atmosphere 25 of hydrogen which was substantially free from electron attaching impurities. The hydrogen had the effect of increasing the mobility of the electrons and, as a result, improved the operating efficiency of the electric discharge device to some extent. However, it was discovered that the hydrogen atmosphere offered less resistance to the movement of ions in the inverse half cycle and the correspondingly increased inverse current nullified at least some of the increased efficiency.

With the above in view, the present invention contemplates operating the electric discharge device in a gaseous atmosphere characterized in that the inverse current is reduced to a minimum and the forward or useful current is substantially increased. In accordance with this invention, the discharge takes place in a gas mixture comprising different free electron gases which, when combined, provide for obtaining increased operating efficiency by insuring a high rate of electron mobility in the forward half cycle and by appreciably obstructing the movement of the ions in the inverse half cycle.

Another object of this invention is to effect the discharge in an atmosphere containing a mixture of at least two gases, one of which has characteristics similar to hydrogen in that it requires a relatively low value of energy for excitation and, is, therefore, advantageous for the 55

production of high mobilities for free electrons. The other gas in the mixture preferably has a higher molecular mass and serves to dampen or obstruct the movement of ions in the inverse half cycle.

Another object of this invention is to provide a method of conditioning the gas mixture, and this object, as well as other objects, will be made more apparent as this description proceeds, especially when considered in connection with the accompanying drawing, wherein:

Figure 1 is a longitudinal sectional view through an electric discharge device embodying this invention;

Figure 2 is a cross sectional view taken on the line 2—2 of Figure 1; and

Figure 3 is a diagram of a circuit embodying the device shown in Figure 1.

In Figures 1 and 2 of the drawing, I have illustrated an electric discharge device 10 having a discharge electrode 11, a collecting electrode 12 and a control electrode 13 electrically positioned between the discharge and collecting electrodes. All of the electrodes are enclosed in an inverted cup-shaped container 14 which, in the present instance, is metal and forms the collecting electrode 12. The lower end of the container is closed by a cap 15 of insulating material having an annular extension 16 surrounding the side wall of the container 14 and having provision for receiving the electrical conductors employed to supply electrical energy to the discharge and control electrodes.

The discharge electrode comprises a vertical rod 17 having the lower end fixed to the cap of insulating material and having a plurality of emitter points 18 extending radially outwardly from the rod at vertically spaced points. The emitter points 18 are directed toward the cylindrical collecting electrode and operate to discharge electricity toward the collecting electrode.

As will be presently set forth, the electric discharge between the emitter points 18 and the collecting electrode 12 is controlled by the control electrode 13. The control electrode 13 comprises a plurality of circumferentially spaced vertical grid bars 19 having the lower ends suitably supported on the cap 15 of insulating material and having the upper ends connected together by a plate 20. The grid bars are respectively positioned between adjacent emitter points 18 in such a manner that the extremities of the points substantially intersect a geometric circle including the outer surfaces of the grid bars 19. It has been found that the above relationship be-

tween the grid bars 19 and the emitting points 18 affords the control of the electric discharge required to obtain high efficiency.

The control electrode 13 is biased with a direct current potential during the operation of the electric discharge by means of an auxiliary electric discharge device 21 having a discharge electrode in the form of a point 22 electrically connected to the grid bars 19 through the medium of a plate 20 and directed toward a collecting electrode 23. The collecting electrode 23 is electrically connected to the discharge electrode 11. Both the electrodes of the auxiliary discharge device 21 are housed in the upper end of the cup-shaped container and, as a result, the auxiliary discharge device forms a unit with the device 10.

In Figure 3 of the drawing I have shown a rectifier circuit embodying an electric discharge device 10 of the above type. In detail, the rectifier circuit comprises a transformer 25 having a primary coil 26 and a secondary coil 27. The primary coil 26 is connected to a source of alternating current potential and one terminal of the secondary coil is connected to the discharge electrode 11. The other terminal of the secondary coil is connected to one side of the load 28 having the other side connected to the collecting electrode 12. A suitable condenser 29 is connected across the load circuit and functions to smooth out the energy delivered to the load.

The control electrode 13 is connected to opposite ends of the secondary coil through the medium of condensers 30 and 31. This circuit supplies an alternating potential to the control electrode and the condensers 30 and 31 operate to impress a potential on the grids of the order and magnitude of the space charge of the control electrode. As pointed out above, a direct current bias is applied to the control electrode 13 by the auxiliary discharge device 21. The application of a biasing potential on the control electrode 13 aids the discharge on the forward half cycle and repels it on the inverse half cycle. It follows, therefore, that an ionization sheath is created immediately adjacent the points 18 on the discharge electrode which expels the discharge current from the sheath to the collecting electrode 12. Also, the biasing potential on the control electrode blocks reverse current on the inverse half cycle and thereby reduces the tendency for the device to arc back to a minimum.

The principal objection to electric discharge devices of the general type set forth above is their lack of efficiency which results from the loss of energy in both the forward and inverse half cycles of the discharge between the electrodes. As briefly pointed out above, when the discharge between the electrodes is effected through an atmosphere containing oxygen, the electrons attach to the oxygen molecules and form ions which have a relatively small mobility as compared to the electrons. Accordingly, ionization in the sheath immediately adjacent the discharge points is suppressed and a loss in current results. In order to overcome this loss in current, it has been proposed to effect the discharge in an atmosphere comprising a free electron gas such as hydrogen, nitrogen, or helium.

Although the above procedure had the effect of increasing the efficiency of the discharge to some extent, nevertheless, it was found that when hydrogen alone was used, the increase in current on the forward or useful half cycle, obtained by reason of the higher mobility of electrons in hydrogen, was nullified to some extent by an in-

crease in current in the inverse half cycle. The mobility of electrons is also increased when the discharge takes place in either nitrogen or helium, but to a lesser extent than in hydrogen. However, these gases have a greater molecular mass than hydrogen and, therefore, retard the movement of ions on the inverse half cycle to a greater extent than hydrogen. Consequently, there is less waste current on the inverse half cycle when operating the discharge in nitrogen and helium.

Another gas that may be used instead of hydrogen is deuterium. This gas has somewhat the same properties as hydrogen insofar as its effect on the electric discharge is concerned and in some instances may be superior because it has a higher molecular mass than hydrogen. In other words, the inverse current is somewhat less in deuterium than in hydrogen but not as small as in nitrogen or helium. Therefore, in order to obtain maximum forward or useful current with the minimum inverse current, I have combined hydrogen or deuterium with nitrogen. Apparently, the percentage of hydrogen or deuterium in the mixture is not especially critical and I have found that efficient sustained high current operation is obtained with a mixture containing from one per cent to sixty per cent of hydrogen or deuterium and the remainder nitrogen.

Helium has also been mentioned as capable of being mixed with hydrogen or deuterium to effect efficient operation of the electric discharge device. I have found that relatively lower onset or gap-drop voltages are obtained when using helium instead of nitrogen. Therefore, the mixture of helium and hydrogen or deuterium may be used where relatively low voltage operation is desired.

It was found that after the electric discharge device 10 was initially loaded with the desired gas mixture, very sluggish operation was obtained and only a relatively small amount of current passed through the device. This performance was due to the fact that the gases were not chemically pure and contained electron-attaching impurities such as oxygen and moisture. However, the efficiency of the device steadily increased as operation of the latter continued and this was due to the fact that the discharge eliminated the electron-attaching impurities in the gas mixture. Therefore, it is desirable to condition the electric discharge device subsequent to loading the device with the desired gas mixture, and this conditioning may be accomplished by effecting a relatively low current discharge of approximately .01 milliampere per discharge point for intervals ranging from fifteen seconds to two hours. This conditioning of the device is permanent and the discharge is changed from an inhibited character to a free electron discharge.

What I claim as my invention is:

1. An electrode discharge device comprising a discharge electrode, a collecting electrode spaced from the discharge electrode, and an atmosphere surrounding the electrodes and characterized in that it consists of a mixture of gases in which electron attachment to molecules does not readily occur.

2. An electric discharge device comprising a discharge electrode having an emitting point, a collecting electrode spaced from the emitting point, a control electrode electrically positioned between the discharge and control electrodes, and a container enclosing all of said electrodes

and filled with a mixture of different free electron gases.

3. An electric discharge device having electrodes cooperating with each other in response to electrical power applied thereto to effect an electric discharge from one electrode to the other, and an atmosphere surrounding the electrodes and comprising a mixture of different gases substantially free from electron attaching impurities.

4. An electric discharge device comprising a collecting electrode, a discharge electrode cooperating with the collecting electrode to effect an electric discharge between the electrodes, and an atmosphere surrounding the electrodes and including a mixture of free electron gases selected from the group consisting of hydrogen, deuterium, nitrogen and helium.

5. An electric discharge device comprising, a collecting electrode, a discharge electrode having an emitting point directed toward the collecting electrode to effect an electric discharge between the point and collecting electrode, and an atmosphere surrounding the electrodes and including a mixture of gases containing hydrogen and nitrogen.

6. An electric discharge device comprising, a collecting electrode, a discharge electrode cooperating with the collecting electrode to effect an electric discharge between the electrodes, a control electrode electrically positioned between the collecting and discharge electrodes to control the discharge, and an atmosphere substantially free from electron attaching impurities surrounding the electrodes and including a mixture of gases containing hydrogen and nitrogen.

7. An electric discharge device comprising, a collecting electrode, a discharge electrode having an emitting point directed toward the collecting electrode to effect an electric discharge between the point and collecting electrode, a control electrode electrically positioned between the collecting and discharge electrodes to control the discharge, and an atmosphere substantially free from electron attaching impurities surrounding the electrodes and including a gas mixture consisting of one per cent to sixty per cent of hydrogen and the remainder nitrogen.

8. An electric discharge device comprising, a collecting electrode, a discharge electrode having an emitting point directed toward the collecting electrode to effect an electric discharge between the point and collecting electrode, and an atmosphere surrounding the electrodes and including a mixture of gases containing helium and hydrogen.

55

9. An electric discharge device comprising a collecting electrode, a discharge electrode directed toward the collecting electrode for effecting an electric discharge between the electrodes, and an atmosphere surrounding the electrodes and including a free electron gas mixture including deuterium and nitrogen.

10. An electric discharge device comprising a collecting electrode, a discharge electrode cooperating with the collecting electrode to effect an electric discharge between the electrodes, a control electrode electrically disposed between the discharge electrode and collecting electrode for controlling the discharge therebetween, and an atmosphere surrounding all of the electrodes and containing a mixture of free electron gases including deuterium and nitrogen.

11. An electric discharge device comprising a collecting electrode, a discharge electrode directed toward the collecting electrode for effecting an electric discharge between the electrodes, and an atmosphere surrounding the electrodes and including a free electron gas mixture including deuterium and helium.

12. In a method of conditioning electric discharge devices having electrodes operating in an atmosphere containing a mixture of different gases, that step which consists in effecting an electric discharge in the atmosphere between the electrodes for a sufficient time interval to substantially eliminate any residual impurities present in the gas mixture.

13. In a method of conditioning electric discharge devices of the type having a discharge electrode and a collecting electrode disposed in an atmosphere of hydrogen and nitrogen, that step which consists in substantially removing any electron attaching impurities from the gas mixture by connecting a high potential between the electrodes to effect an electric discharge between the electrodes through the gaseous atmosphere.

14. In a method of conditioning electric discharge devices of the type having a discharge electrode and a collecting electrode disposed in an atmosphere of gases selected from the group consisting of hydrogen, deuterium, nitrogen and helium, that step which consists in effecting an electric discharge between the electrodes through the gaseous atmosphere for a sufficient time interval to substantially eliminate any electron-attaching impurities from the atmosphere.
